A. MAAKE.
CURTAIN WINDOW FOR VEHICLES.
FILED SEPT. 1, 1922.

Inventor

Arthur Maake

By S. S. Thomas

Attorney

UNITED STATES PATENT OFFICE.

ARTHUR MAAKE, OF DETROIT, MICHIGAN.

CURTAIN WINDOW FOR VEHICLES.

Application filed September 1, 1922. Serial No. 585,601.

To all whom it may concern:

Be it known that I, ARTHUR MAAKE, citizen of the United States, residing at Detroit, county of Wayne, State of Michigan, have invented a certain new and useful Improvement in Curtain Windows for Vehicles, and declare the following to be a full, clear, and exact description of the same, such as will enable others skilled in the art to which it pertains to make and use the same, reference being had to the accompanying drawings, which form a part of this specification.

My invention relates to curtain windows for vehicles shown in the accompanying drawings and more particularly described in the following specification and claims:

It is well known that transparent celluloid has been largely used for windows for the curtains of motor driven vehicles but its use is objectionable because it soon becomes dull, discolored and broken.

Sheet glass has therefore been employed because of its greater transparency, but difficulty has been experienced in providing a suitable supporting frame adapted to grip the glass so that it will not "rattle" from the vibration of the vehicle. To this end supporting frames of sheet-lead have been employed by me, bent into channel-like form in cross-section to receive the margin of the glass, the walls of the frame being subsequently compressed to grip the glass. It has been found in practice however that the vibration of the vehicle will sooner or later cause the lead frame to bend under the pressure of the glass which becoming loose is apt to rattle or drop from the frame.

Rigid metal frames have also been employed for supporting the glass but they cannot be easily compressed into impinging relation with the glass to secure the latter against vibration.

Among other advantages gained by the use of sheet-lead as a supporting frame is that the walls of the frame can be readily spread apart for the insertion or removal of the glass, and after inserting the glass the walls of the frame may be compressed to tightly grip its marginal edge.

As stated before however in actual practice it has been found that the vibration of the vehicle causes the glass to act upon the lead frame thereby loosening the glass so that it soon begins to rattle in the frame and

oftentimes the latter is bent sufficiently to permit the glass to drop out.

The primary object therefore of this invention is to provide means adapted to prevent the walls of a lead frame from spreading as a result of the vibration of the vehicle;—advantage being taken of the use of the lead frame to grip the glass and to provide for the latter an elastic supporting bed. The glass being readily gripped between the side walls of the frame when compressed it may be released by merely bending one of the walls away from the glass which may then be removed or replaced.

One of the features therefore of this invention is to provide a plurality of rigid metallic channel members, covered with cloth similar to the curtain lining that it may present a finished appearance; the rigid channel members being adapted to overlap the inner wall of each of the four sides of the lead frame; the rigid channel members of the frame being also secured together at their respective ends by bolts extending through said rigid channel members, the curtain, and the reinforcing member located back of the curtain, and overlapping the outer wall of the lead frame.

With the foregoing and other objects in view which will appear as the description proceeds the invention further resides in the combination and arrangement of parts and in the details of construction hereinafter described and claimed, it being understood that changes may be made in the precise embodiment of the invention herein disclosed without departing from the spirit of the same.

In the drawings accompanying this specification:

Figure 1 is a side elevation of the usual touring type of automobile fitted with a top, and side curtains in which the windows are installed.

Figure 2 is a fragmentary elevation of details of construction showing a window light installed in the curtain opening, as viewed from the inside of the curtain,—a portion of the lining being removed to disclose the reinforcing members enclosed between the curtain and lining.

Figure 3 is a fragmentary perspective view of one corner of the curtain showing the glass supported in the channel shaped strips of the lead frame with the overlap.

ping rigid metallic strips covered with cloth corresponding with the lining of the curtain. The view also shows the corner bolt for securing the members of the rigid metallic frame to the curtain in co-operating relation with the sheet-lead frame.

Figure 4 is a fragmentary perspective view showing the lead frame overlapping and bearing upon the marginal edge of the glass,—showing also the curtain adjacent to the outer reinforcing member, with the marginal edge of the curtain extending between the glass and the outer wall of the lead frame, and also the rigid metallic member, covered with a cloth lining and overlapping the inner wall of the lead frame that it may impinge upon the glass, and at its lower edge upon the lining of the curtain.

Figure 5 is a fragmentary perspective view of the rigid channel member covered with a fabric lining.

Referring now to the letters of reference placed upon the drawings:

A, denotes an automobile, B, its top and C, its side curtains provided with window openings D. E, designates U-shaped strips formed of sheet-lead lodged between the curtain and its lining F. G, is a reinforcing member formed of cardboard or the like located between the curtain C, and its lining and adjacent the outer wall of the lead frame;—the curtain and reinforcing members are sewed together as indicated by the dotted line H, in Figures 2 and 3. I, indicates a sheet of glass having its marginal edges projecting into the channels formed by the lead frame. The curtain C has a "return-bend" extending between the glass and the outer wall of the lead frame, as indicated in Figure 4. J, denotes a rigid channel member formed of sheet steel covered with a fabric K,—preferably the same as that employed for the lining of the curtain. L, are bolts extending through the curtain,—the reinforcing member G overlapping the outer wall of the lead frame,—and the channel members J, thus securing the latter together and affording a rigid support for the walls of the lead frame to secure it against spreading either under wind pressure or the vibration of the glass. M, M, are wooden reinforcing strips secured between the curtain and its lining by lines of stitches on each side of the reinforcing strips.

Having now indicated the several parts by reference letters the construction of the device will be readily understood.

To replace a broken light the channel members J, overlapping the inner wall of the lead frame are first removed, the wall of the lead frame overlapping the glass is then pried away from the glass sufficiently to permit the removal of the latter,—a new light of glass is then inserted in the frame

and the lead walls bent back to again impinge upon the marginal edge of the glass. The channel members J, are then replaced to overlap the lead walls and are secured in position by bolts extending through the curtain at the respective corners of the frame. As previously explained the "rigid" frame serves to support the walls of the lead frame and secures them against bending through wind pressure upon the glass, or as a result of the vibration of the vehicle. By covering the rigid channel members with a fabric similar to the curtain lining a finished appearance is given to the inside of the curtain and the lead frame is concealed from view.

Having now described my invention what I claim is:

1. In a device of the character described, the combination of a curtain provided with a window opening, a channel frame formed of sheet lead fitted to the curtain surrounding its window opening, a light of glass having its marginal edges extending into the said channel frame of sheet lead, a plurality of rigid members adapted to overlap the wall of the lead channel frame, and means for securing said rigid members together and to the curtain, whereby the walls of the lead frame may be supported in impinging relation with the glass to secure against lateral movement of the glass in the frame.

2: In a device of the character described, the combination of a curtain provided with a window opening, a channel frame formed of sheet lead fitted to the curtain surrounding its window opening, a light of glass having its marginal edges extending into the said channel frame of sheet lead, rigid channel bars adapted to overlap the wall of the lead channel frame, and means for securing said channel members together and to the curtain, whereby the walls of the lead frame may be supported in impinging relation with the glass to secure the latter against movement in the frame.

3. In a device of the character described, the combination of a curtain provided with a window opening, a reinforcing member surrounding the window opening, a lining also provided with a window opening stitched to the curtain and reinforcing member, a lead frame of channel-like form surrounding the window opening, a light of glass having its marginal edges extending into said lead channel frame, a plurality of rigid metallic channel members overlapping the inner walls of the lead frame having marginal edges respectively impinging upon the glass and upon the curtain member, and bolts extending through the ends of the rigid channel members, the curtain and reinforcing members to secure the rigid channel members contiguous to the lead channel members whereby the walls of said lead

channel members may be held in impinging relation to the marginal edge of glass.

4. In a device of the character described, the combination of a curtain provided with a window opening, a reinforcing member surrounding the window opening, a lining also provided with a window opening stitched to the curtain and reinforcing member, a lead frame of channel-like form 10 rounding the window opening, a light of glass having its marginal edges extending into said lead channel frame, and a return-bend of the curtain also extending into said lead frame between the glass and its outer 15 wall, a plurality of rigid metallic channel members overlapping the inner walls of the lead frame having marginal edges respectively impinging upon the glass and upon the curtain member, and bolts extending 20 through the ends of the rigid channel members, the curtain and reinforcing members to secure the rigid channel members contiguous to the lead channel members whereby

the walls of said channel members may be held in impinging relation to the marginal 25 edge of the glass.

5. In a device of the character described, the combination of a curtain provided with a window opening, a channel frame formed of sheet lead fitted to the curtain surrounding its window opening, a light of glass having its marginal edges extending into the 30 said channel frame of sheet lead, a plurality of rigid metallic members overlapping the inner wall of the lead channel frame, whereby 35 the walls of the frame are held against spreading, means for securing said rigid metallic members together, and a fabric covering for said rigid metallic members.

In testimony whereof, I sign this specification in the presence of two witnesses.

ARTHUR MAAKE.
